CLAIM

The ornamental design for a display screen or portion thereof with animated card communication interface, as shown and described.

DESCRIPTION

FIG. 1 is a first image in a sequence for a display screen or portion thereof with animated card communication interface showing the new design;

FIG. 2 is a second image thereof; and,

FIG. 3 is a third image thereof.

The appearance of the animated images sequentially transitions between the images shown in FIGS. 1 through 3.

The process or period in which one image transitions to another forms no part of the claimed design.

The elongated dashed lines forming a horizontal line in FIGS. 1 through 3 are included in the claimed design.

The long-dashed broken lines forming a horizontal line in FIGS. 1 through 3 are included in the claimed design. The short-dashed broken line showing of display screen or portion thereof and dashed showing of text is included for

the purpose of illustrating portions of the article and forms no part of the claimed design; the short-dashed showing of a device is included for the purpose of illustrating environmental structure and forms no part of the claimed design.
